ELECTROMAGNETIC POSITION INDICATING DEVICE

Howard D. Warshaw, San Jose, Calif., and Kenneth E. Wakefield, Princeton, N.J., assignors, by mesne assignments, to the United States of America as represented by the Secretary of the Army

Filed Feb. 23, 1962, Ser. No. 175,379

2 Claims. (Cl. 340—196)

This invention relates to a position indicating device, and more particularly to an electromagnetic position indicating device for indicating a linear or angular position with a high degree of accuracy.

In the prior art it is known to use a position indicating mechanism consisting of a make and break switching circuit connected to a movable member whose position is to be monitored. The switching circuit usually has a contact brush in contact with a fixed circular surface comprising a series of contact strips separated from one another electrically and connected respectively in the circuits of a plurality of indicator elements such as, for example, electric lamps. Any movement of the movable member will cause the contact brush to close the circuit between one of the contact strips and a lamp, thereby causing the lamp to light and indicate, to some degree, the position of the movable member. One difficulty with this type of position indicating device is that the contact friction between the brush and circular contact strips causes an undesired loading or damping of the movable member. Another disadvantage is that the switching circuit has a relative short life and requires constant maintenance.

Accordingly, it is an object of this invention to provide a position indicating device having no contacting surfaces, thereby greatly reducing the loading of the movable member and extending the operational life of the device.

Another object of this invention is to provide an improved indicating device which is not unduly large or complex.

Still another object of this invention is to provide an indicating device of the electromagnetic type which gives greater accuracy than heretofore obtainable.

A further object of this invention is to provide an indicating device of the electromagnetic type which does not depend on a constant supply voltage or frequency.

A still further object of this invention is to provide an electromagnetic position indicating device which is not affected by changes in external conditions surrounding the device nor by the position in which the device is mounted or placed.

In accordance with the invention, the electromagnetic position indicating device is provided with a magnetic core having a primary winding secured thereto. The primary winding is connected to a signal source which energizes the winding so as to produce a magnetic flux in the magnetic core. The magnetic core is provided with a plurality of fixed, parallel laminated strips upon which is wound a secondary coil. These secondary coils are connected in pairs in such a manner that the voltage in each coil is of opposite polarity in respect to the other coil. The magnetic core is also provided with a movable arm which is constructed of magnetic material and which is adapted to move in relationship to the laminated strips. The movable arm is attached to a movable member whose position is to be monitored. The pairs of secondary coils are attached to an indicating device through a switching circuit which is adapted to select which pair of coils is to be in circuit with the indicator device at any given time. Any movement of the movable member will be transmitted to the movable arm causing the arm to move and thereby change the magnet coupling through the strips. This change in magnet coupling will cause a corresponding

2

change in the voltage fed to the indicating device by the secondary coil, thus giving an indication of the position of the movable member.

The novel features of this invention as well as the invention itself, both as to its organization and method of operation, will best be understood from the following description, when read in connection with the accompanying drawing, in which like reference numerals refer to like parts, and in which:

10 FIGURE 1 is a diagrammatic view illustrating one form of the electromagnetic position indicating device;

FIGURE 2 is an enlarged view of a portion of FIGURE 1;

15 FIGURE 3 is a graphic illustration of the wave forms explanatory of functions to be described in connection with the above figures; and

FIGURE 4 illustrates an alternative arrangement of the electromagnetic position indicating device.

In FIGURE 1, the reference charger 1 designates generally an electromagnetic position indicating device. The common magnetic core 2 of the device is constructed of a magnetic material such as, for example, several laminations of magnetic steel. A portion of the magnetic core 2 is formed by a plurality of fixed, parallel strips 3a-3h. These strips are constructed of magnetic material and are preferably formed of several layers of laminations as is well known in the art. A movable arm or core portion 4 is secured to the common magnetic core 2 by a pivot joint 5 which allows the arm to rotate about the pivot point. The movable arm is constructed of magnetic material which is, preferably, of the laminated type. The arm 4 has a cross sectional area such that the greater portion of the magnetic flux through the arm is linked only to one laminated strip when the arm and strip are juxtaposed in end to end relation. The extreme end 4a of the movable arm 4 moves in an arc formed by the faces or ends of the parallel laminated strips 3a-3h while the other extreme end of movable arm 4 is provided with a nut 6 and threaded shaft portion 7. By properly adjusting the nut upon the threaded shaft, the movable arm may be balanced. If desired, this balancing arrangement may be omitted or replaced by other balancing devices as are well known in the art. A movable member 8, whose angular position is to be monitored, is connected to the arm 4 by connecting means 9 in such manner that any angular movement of member 8 will cause arm 4 to rotate about pivot 5 thereby causing end 4a to move in relationship to the fixed laminated strips 3a-3h.

50 Wound around the strips of the common magnetic core 2 is a primary or energizing coil 10 which is connected to a signal source 11 by connecting leads 12. The signal source 11 may be, for example, an electronic signal generator operating at a frequency between 1,000 and 20,000 cycles per second. Wound around each of the laminated strips 3a-3h is a secondary coil 13a-13h with each of said coils being spaced from the end of their respective laminated strips so as to form an arc as shown by FIGURE 1. The coils 13a-13h are grouped into adjacent pairs 13a-b, 13c-d, 13e-f, 13g-h and are connected together so that the voltage produced by each coil is opposite in sign with respect to the voltage produced by the other coil of the pair. One lead from each pair of coils 13a-b, 13c-d, 13e-f, 13g-h is connected to a common conductor 14 while the other lead is connected to conductors 15-18, respectively.

60 The common conductor 14 is connected directly to one terminal of an indicating device 20 which may be, for example, a vacuum tube voltmeter. The conductors 15-18 are connected to various terminal contacts of a switch 19 so that, by adjusting the movable contact of the switch 19, various pairs of the secondary coils may be switched into circuit with the indicator 20.

In understanding the mode of operation of the electromagnetic position indicating device 1, assume that the signal source 11 is operating to produce a magnetic flux in the common magnetic core 2 and that the movable member 8 is so located that the movable arm 4 is positioned between the laminated strips 3e-3f. The switch circuit 19 is adjusted so as to connect conductor 17 in circuit with the indicating device 20 thereby establishing an electrical circuit through coils 13e-f, conductor 17, indicator device 20 and the common conductor 14.

As stated above, the secondary coils are arranged in adjacent pairs, the coils of each pair being so coupled together that the voltage induced in each coil is of opposite polarity from the voltage induced in the other coil. The reversing of the polarity of the voltage induced in each adjacent coil may be accomplished by winding the coils in reverse one from the other or, if the coils are wound in the same direction, by properly cross connecting the two coils together.

With the movable arm 4 equally positioned between laminated strips 3e-3f, the magnetic coupling path through the arm, laminated strips 3e-3f, and common magnetic core 2 will be equal. The voltage thus induced in the secondary windings 13e-13f by the change in magnetic flux, produced by the generator 11, will be equal in amplitude but opposite in polarity. These voltages, being equal in amplitude but opposite in polarity, will effectively cancel one another and give no reading on the indicator 20. The absence of any voltage indicates that the movable arm is exactly positioned between the laminated strips 3e-3f as shown by point A on the graph of FIGURE 3.

Now assume that the movable member 8 is relocated so as to move arm 4 closer to the face of laminated strip 3e as shown by FIGURE 2. It becomes obvious that the magnetic coupling between the laminated strip 3e and movable arm 4 will become greater and that the voltage produced in the secondary winding 13e will increase while the magnetic coupling between the laminated strip 3f and the arm 4 will decrease causing a drop in the voltage produced in the secondary coil 13f. The opposing voltages produced by the two coils 13e-13f are no longer equal in amplitude and therefore will not cancel out. The voltage difference produced by totaling the voltages will be sensed by the indicator 20 which will indicate a movement of the member 8. This new position of the movable member 8 is shown as point B on the graph of FIGURE 3.

FIGURE 3 shows the additional voltages produced by movement of the arm 4 to various positions between the laminated strips 3a-3h.

In FIGURE 4, a modified form of the electromagnetic position indicating device 1 is shown in which like reference numerals refer to like parts as described in relation to FIGURES 1 and 2 above. In this figure, the ends or faces of the laminated strips 13a-13h have been constructed in a common plane with the end of movable arm 21. Arm 21 is supported by a bearing 22 and is adapted to slide freely in a linear manner. Coupled to the arm 21 through coupling means 23 is a linearly movable member 24 which, when moved, causes arm 21 to move thereby indicating a change in position on indicator 20. Since there is no physical contact between the movable arm and the laminated strips, a housing means 25 may be inserted between the laminated strip faces and the movable arm to thereby seal a portion of the device without adversely affecting the operation of the indicator. Such a housing 65 may be desirable under certain conditions in order to

protect a part or all of the device from external conditions.

The device is not noticeably affected by stray fields of magnetic flux. However, if the device is subject to extreme stray fields of magnetic flux, the entire common magnetic core and movable arm may be housed in a shield enclosure, or a proper choice of input frequency together with a suitable filter in the output circuit of the secondary coils would eliminate the effect of the stray fields upon the device.

From the above description, it is apparent that our invention can be utilized to indicate the position of a mechanism having either angular or linear travel. The device is independent of supply voltage and frequency over wide ranges and can be made virtually independent of pressure, temperature or position of mounting. There need be no physical contact between the movable arm and the stationary laminated strip, hence the movable arm and strips, if desired, may be isolated electrically, thermally, or separated by a diaphragm for atmospheric isolation. Also the absence of any physical contact between the movable arm and laminated strips prevents the movable member from being unduly loaded.

While we have described our invention in its preferred embodiments, we desire that it is be understood that modifications may be made and that no limitations are intended other than may be imposed by the scope of the appended claims.

What is claimed is:

1. Apparatus for indicating the position of a movable member comprising, a common magnetic core member having a plurality of pairs of strip finger-like projections thereon, the common magnetic core having a movable arm portion mounted to be moved relative thereto, the movable arm being positionable adjacent to a selected pair of the strip finger-like projections whereby a magnetic circuit will be established through the common magnetic core, through the movable arm and through the selected pair of strip finger-like projections back to the common magnetic core member, means to induce an alternating magnetic flux in each finger of the magnetic circuit, and coil means on each finger, connected in pairs, to sense the flow of magnetic flux through each pair of strip-like finger projections, said coil means of the selected pair of fingers being connected together such that electric currents in the coils are equal but opposite in direction so as to cancel one-another when magnetic flux is flowing equally in each finger of a pair of projections, and such that electric currents in the coils do not cancel and therefore there is a net flow of current in the coils when the magnetic flux in one of the fingers of a pair exceeds that of the other finger of the pair.
2. Apparatus as set forth in claim 1, and means to monitor current flow, and absence thereof, in the coils to thereby indicate the position of the movable arm relative to the pairs of strip finger-like projections.
